UNITED STATES PATENT OFFICE.

ARBA P. STANLEY, OF COLUMBUS, AND EDGAR A. STANLEY, OF YOUNGSTOWN, OHIO.

BURNER FOR LIQUID AND GASEOUS FUELS.

Application filed February 14, 1921. Serial No. 444,643.

Our invention relates to burners for liquid and gaseous fuels and has for its aim the production of a novel type of burner that may be utilized with equal facility in the consumption of coal-oil, fuel-oil, gasoline, or natural or artificial gas. Either liquid or gaseous fuel may be used separately or together in our novel form of burner.

Our burner is rendered particularly adaptable to the use of liquid fuel by the provision of a novel means of injecting the fuel into the gas generating chamber of our device. This novel means contemplates the utilization of steam as a vehicle by which the fuel is picked up and carried into the generating chamber as a mist or spray. The steam thus utilized performs the additional function of attacking the carbon produced by the cracking of the fuel and turning this carbon into water gas. The fuel is cracked at about three hundred and fifty (350) degrees F. and the carbon is converted into water gas whether it has been deposited on the walls of the generating chamber or carried through the chamber with the gaseous elements of the fuel. Thus, one important phase of our invention arises from the fact that the steam will greatly reduce the carbon deposits in the generating chamber and, in fact, practically eliminates these deposits.

More specifically, our invention contemplates the provision of a novel construction of burner embodying a main burner pipe which may be fed from one end by natural or artificial gas and which may be fed from the other end by a volatilized liquid fuel preferably carried to the generating chamber by steam. In our preferred structure of burner, the volatilization of the liquid fuel and the generation of the steam is effected within the burner itself. Not only this, but the burner construction is such that the liquid and gaseous fuel can be introduced and utilized simultaneously.

Our novel structure of burner is such that it includes a means for pre-heating the air to be mixed with the gas so as to ensure a better mixture and a better burning. It also desirably includes a series of mesh screens or reticulate members to further facilitate mixing.

Further important advantages of our novel structure of burner will appear as this description progresses. The preferred embodiment of our invention is shown in the

accompanying drawings wherein similar characters of reference designate corresponding parts and wherein

Figure 1 is a transverse section taken through our burner. 60

Figure 2 is a section taken on line 2—2 of Figure 1.

Figure 3 is a section taken on line A—B—C—D—E of Figure 1.

Figure 4 is a section taken on line A—B—D—E of Figure 1. 65

In the drawings, the main burner pipe may be designated 1. It comprises a horizontal pipe of substantial cross-sectional area to the left end of which is connected a natural or artificial gas inlet pipe 2 under the control of a valve 3. This main burner pipe 1 is provided in its upper wall with a series of ports 4 preferably arranged in separate rows as shown in Figure 2. 70

The right-hand end of the pipe 1 is connected with an elbow construction comprised of elbow units 5 and 6 (see Figure 4), these elbow units being connected together by an externally threaded sleeve 7 that screws into 80 opposing ends of the units 5 and 6. The lower end of the unit 5 is internally threaded to screw upon threads on the right-hand end of the pipe 1. The upper end of the unit 6 is also internally threaded for the reception of the external threads of a liquid fuel pipe 8. This liquid fuel pipe 8 is in parallelism with the pipe 1 but is to one side of a vertical plane through this pipe 1 (see Figure 1). 85

Likewise disposed in parallelism with the pipes 1 and 8 is a steam pipe 9. This steam pipe 9 is above pipe 1 but is to the opposite side of the vertical plane through the pipe 1 (see Figure 1). 90

The main burner pipe 1 passes through openings in an end casing 10 and a cross partition 11. Disposed outside of the partition 11 and sufficiently spaced therefrom to provide room for the elbow units 5 and 6 is the opposite end casing 12. The end casings 10 and 12 are provided with feet 13 and 14 and immediately above these feet carry a bottom plate 15 with an air inlet 16 arranged therein. 100

This bottom plate 15 rests upon the feet 14 and is provided at its side with upwardly extending side pieces 17 and 18 that extend approximately half way up the sides of the burner structure. At their upper ends, they 105

are inwardly bent to form hoods 19 and 20 and then are downwardly bent into parallelism with and spaced relation to the side pieces 17 and 18 as at 21 and 22. Cooperating with this structure is a baffle plate structure having a base 23 and upstanding leg members 24 and 25. These pieces 15, 17, 18, 19, 20, 21, 22, 23, 24 and 25 extend the full length of the space between the end plate 10 and the partition 11 and cause the incoming air to traverse tortuous paths in its approach to the chamber 26 beneath the burner pipe 1.

Mounted between the members 21 and 22 and forming the top of the chamber 26 is the burner pipe 1 together with certain screen structure now to be described. The screen structure takes the form of spaced screens or reticulate plates 27 and 28. The screen or reticulate member 28 is of such form that the openings therethrough are relatively smaller than the openings through the member 27. These reticulate members are in the form of inverted U's and the member 27 embraces the main burner pipe 1 in spaced relation thereto while the member 28 embraces the member 27 and in spaced relation thereto. At its lower end, the member 28 is provided with lateral reticulate extensions 29 which extend into abutting relation to the lower ends of the depending baffle plates 21 and 22.

The left-hand end of the pipe 8 is threaded into a portion of the end plate through which extends a duct 30 whose outer end is provided with a nozzle space. A nozzle 31 extends into this space part way and this nozzle may be supplied with a liquid fuel under pressure and under the control of a needle valve 32 or by means of a similarly controlled fuel nozzle at right angles thereto such as indicated in dotted lines at 33. The needle valve 32 is operated by a handle wheel 34 and a similar structure may be provided for the nozzle structure 33. The needle valve 32 and the fuel nozzle at 33 make possible the delivery of two different kinds of fuel to the pipe 8. Either fuel may be used as desired.

The left-hand end of the steam pipe 9 is likewise threaded into the end casing 10 while its right-hand end is capped as at 35. Concentrically disposed within this steam pipe 9, we have provided an inner tube 36 which is to be fed with water under pressure under the control of a needle valve 37 having a hand-wheel 38 on its stem. The needle valves 32 and 37 are desirably operated in unison and proportionately and this is ensured by the provision of intermeshing gears 39 and 40. However, these valves may be operable independently.

A means for starting the burner is comprised in the trough 41 which is mounted beneath the pipe 8 and which may be fed

with a small charge of fuel-oil through the pipe 42, to be lighted through the opening 50.

In the operation of our burner with liquid fuel, fuel-oil may be introduced into the igniting trough 41 and ignited and the needle valve 32 may be opened to permit the admission of liquid fuel into the pipe 8. Vaporization will take place in a short time. At the same time, due to the intermeshing relation of the gears 39 and 40, water is introduced into the inner tube 36 and the heat within the burner results in a generation of steam. This generation of steam takes place as the water leaves the inner tube 36 or before and the steam so generated passes downwardly through the duct 43 alongside of the injector nozzle 31. Passing by the injector nozzle 31, it picks up the liquid fuel being delivered to this injector nozzle under pressure and carries it as a mist or spray into the pipe 8 which constitutes the gas generating chamber. The gas generated in this chamber passes through the elbow units 6 and 5 and the sleeve 7 and thence into the main burner pipe 1, whence it passes upwardly through the ports 4. As it emerges from the ports 4 it meets the air which has been pre-heated and delivered into the space between the main burner pipe 1 and the reticulate member 27. Then, it passes through the reticulate member 27 and into the passage or space between the members 27 and 28 where it is supplemented by the pre-heated air which has risen into this passage from the chamber 26. At this time, the burner goes into full operation and the full heating effect of the flame is applied to the gas generating chamber pipe 8 as well as to the steam pipe 9.

When the temperature in the gas generating chamber is approximately three hundred and fifty (350) degrees F. or over, there is a tendency for the carbon element from the cracked fuel to deposit on the walls of this gas generating chamber. However, the steam which is coming into this gas generating chamber and passing through the same, is constantly attacking this carbon deposit in addition to its normal function as a vehicle for the fuel so that practically all of the carbon is converted into water gas which is finally consumed with the gaseous elements of the fuel.

By reference particularly to Figure 1, it will be apparent, as indicated by the arrows, that the air enters the opening 16 in the base plate 15 and pursues a tortuous passage upward and inward and then downward until it reaches the chamber 26. By this time, it is thoroughly heated and then passes upwardly between and through the reticulate members 27 and 28 in the manner previously described. This pre-heating of the air ensures a more complete and efficient combustion.

Furthermore, our novel method of introducing air to the flame at separate zones results in a more thorough mixing and burning of the products of combustion with a consequent increase in the efficiency of the burner. However, our burner may be built using air without pre-heating before it enters the burners for mixing and burning.

One mixing screen or reticulate plate may be used instead of the two as shown. Likewise, the air and gas may be burned together without any mixing screen or reticulate plate. An important advantage is gained by mixing the air and gas at the burner ports, in that they are burned together immediately after mixing without being carried through long pipes in a mixed combustible state. This will prevent ignition and burning in the pipe before the burner ports are reached.

In the operation of our burner, liquid fuel may be allowed to run through the steam injecting nozzle into the gas generating chamber without the utilization of steam as a vehicle. This will permit turning of the liquid fuel into fuel-gas at starting. Then, the water and steam unit can be placed in operation shortly afterwards. The burner can be operated on liquid fuel entirely without the steam injecting feature although we prefer the use of this steam.

Natural or artificial gas may be used as the fuel agent merely by turning on the valve 3 and permitting the gas to flow directly into the left-hand end of the main burner pipe 1. This gas passes upwardly through the ports 4 and is mixed with the pre-heated air as described in the use of liquid fuel gas. It is possible, also, to use natural or artificial gas and liquid fuel at the same time, the natural or artificial gas passing into one end of the main burner pipe 1 and the liquid fuel gas being vaporized and delivered into the opposite end of the main burner pipe 1.

It will also be understood that it is possible with our device to use either natural or artificial gas for starting. Likewise, gasoline may be introduced into the gas generating chamber 8 for starting the burner.

We have shown a burner construction designed for a small heater with only one burner pipe, one gas-generating chamber and one steam generating chamber. Obviously, it is possible to build our device with any number of burner pipes connected to one gas generating chamber and one steam generating chamber. On the other hand, we may utilize a number of complete units comprising a steam generating chamber, a gas generating chamber, and one or more burner pipes and these with all necessary valve connections and piping can be built into a heater, a furnace or any other fuel-consuming unit.

A very desirable feature of our device is that we are able to ensure any proportional admission of water and liquid fuel. This is attainable by means of the intermeshing gears 39 and 40 which may vary with relation to each other. Our units may be built without this attachment, however, and the proportional delivery of fuel and water be governed by the desires of the operator.

Obviously, our invention may take many different forms, in that we may duplicate some units or we may omit some units. All such changes, however, are within the scope of the claims appended hereto.

Having thus described our invention, what we claim is:

1. A burner structure comprising a pipe with flame ports therein, means for introducing a gaseous fuel into one end of said pipe, and means for introducing a vaporized liquid fuel into the other end of said pipe.

2. A burner structure comprising an enclosing casing, a main burner element, a gas generating chamber, a steam generating chamber, said element and chambers being within said casing, and subjected to the heat therein, and a reticulated element forming a hood over said burner member for directing preheated air to said burner member.

3. A burner structure comprising a main burner element, means for introducing a gaseous fuel into one end of said burner element, a generating chamber connected to the other end of said main burner element, means for introducing a liquid fuel to said generating chamber, said generating chamber being so located as to be subject to heat from said main burner element to vaporize the fuel introduced, and means for producing steam within the burner structure and introducing it into said generating chamber.

4. A burner structure comprising a main burner element, a gas generating chamber, means for introducing liquid fuel into said chamber as a spray or mist, a steam generating chamber, means for conducting the steam generated in said steam generating chamber into said gas generating chamber, said gas generating chamber being connected to one end of said main burner element and means for introducing a gaseous fuel into the other end of said element.

5. Burner structure comprising a main burner element, a gas generating chamber, a steam generating chamber, an inner tube within said steam generating chamber and delivering thereto a means for controlling the admission of liquid fuel to said gas generating chamber, means for controlling the admission of water to said steam generating chamber and gearing connecting said last two means so as to proportion the liquid fuel and water admitted thereto.

6. Burner structure comprising a burner pipe with flame ports therein, means for in-

roducing fuel into both ends of said pipe, a casing enclosing said pipe, and tortuous passageways for conducting admitted air past heating surfaces within said casing to the point of burning.

7. Burner structure comprising a burner pipe with flame ports therein, means for introducing fuel into both ends of said pipe, an enclosing casing with an opening in its base, tortuous passages adjacent the walls of said casing and leading to a point proximate the delivery ports of said pipe.

8. Burner structure comprising a main burner element having delivery ports therein, means for feeding gas to one end of said main burner element, means for introducing vaporized liquid fuel to the other end of said burner element for delivery through said ports, and means for delivering pre-heated air to a point adjacent said delivery ports and upon the outside of said main burner element.

9. A burner structure comprising a main burner element, a gas generating chamber,

a steam generating chamber, said main burner element being connected in series with said gas generating chamber, said gas generating chamber being connected in series with said steam generating chamber, both said gas generating chamber and said steam generating chamber being located above said main burner structure and subjected directly to the heat of said main burner element and a reticulate plate located between said burner and said chambers.

10. A burner structure comprising a main burner element, a gas generating chamber, a steam generating chamber and a casing, said chambers being connected in series with each other and with one end of said burner element, said steam generating chamber being subjected to heat on all of its sides and means for introducing a separate fuel at the other end of said burner element.

In testimony whereof we hereby affix our signatures.
